(57) **CLAIM**

The ornamental design for a housing for water analyzer, as shown and described.

DESCRIPTION

FIG. 1 is a front, right-side, top perspective view of a housing for water analyzer, showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a front, left-side, bottom perspective view thereof; and,

FIG. 9 is an enlarged view of area 9 in FIG. 3.

The dot-dash chain lines depict an enlargement area, and thus form no part of the claimed design.

1 Claim, 9 Drawing Sheets
